US00D912683S

(12) **United States Design Patent** (10) Patent No.: **US D912,683 S**
Patel et al. (45) Date of Patent: **** Mar. 9, 2021**

(54) **DISPLAY SCREEN WITH GRAPHICAL USER INTERFACE**

(71) Applicant: **Google LLC**, Mountain View, CA (US)

(72) Inventors: **Kunal Patel**, San Francisco, CA (US); **Brendan Pascoe**, San Francisco, CA (US); **David Chiu**, San Francisco, CA (US); **Rachel Been**, San Francisco, CA (US); **Sameer Kumar Bansal**, San Francisco, CA (US)

(73) Assignee: **GOOGLE LLC**, Mountain View, CA (US)

(**) Term: **15 Years**

(21) Appl. No.: **29/640,266**

(22) Filed: **Mar. 13, 2018**

(51) LOC (13) Cl. **14-04**

(52) U.S. Cl.

USPC **D14/485**; D14/491

(58) **Field of Classification Search**

USPC D14/485-495
 CPC G06F 3/048; G06F 3/0481; G06F 3/04817; G06F 3/0482; G06F 3/0483; G06F 3/04842; G06F 3/0485; G06F 3/04855; G06F 3/0486; G06F 3/0488; G06F 3/04886; G06F 9/4443; G06F 17/211; G06F 17/212

Primary Examiner — Jack Reickel

(74) Attorney, Agent, or Firm — Plumsea Law Group, LLC

(57) **CLAIM**

The ornamental design for a display screen with graphical user interface, as shown and described.

DESCRIPTION

The sole FIGURE is a front view of a display screen with graphical user interface, showing the new design. The uneven-length broken lines define a display screen and form no part of the claimed design.

1 Claim, 1 Drawing Sheet
